CLAIM

The ornamental design for a table lamp, as shown and described.

DESCRIPTION

FIG. 1 is a front perspective view of a table lamp showing my new design;

FIG. 2 is a rear view thereof;

FIG. 3 is a front view thereof; and,

FIG. 4 is a top plan view thereof.

The dashed broken lines in the figures illustrate portions of the table lamp that form no part of the claimed design. Views of the article not shown form no part of the claimed design.

1 Claim, 4 Drawing Sheets
